(57) **CLAIM**

The ornamental design for a sign, as shown and described.

DESCRIPTION

FIG. 1 is a perspective view of a sign, showing my new design;
FIG. 2 is a left side view thereof;
FIG. 3 is a right side view thereof;
FIG. 4 is a front view thereof;
FIG. 5 is a back view thereof;
FIG. 6 is a bottom view thereof; and,
FIG. 7 is a top view thereof.

The article is shown with wavy symbolic breaks in its
length. The appearance of any portion of the article between
the break lines forms no part of the claimed design. The
broken lines shown in the figure drawings show portions of
the article that form no part of the claimed design.
